UNITED STATES PATENT OFFICE.

ARVID J. MALMBERG, OF ERIE, PENNSYLVANIA, ASSIGNOR TO ANNA MALMBERG, OF ERIE, PENNSYLVANIA.

METALLIC DOOR.

1,129,043.

Specification of Letters Patent. Patented Feb. 16, 1915.

Original application filed November 8, 1913, Serial No. 799,889. Divided and this application filed November 2, 1914. Serial No. 869,874.

To all whom it may concern:

Be it known that I, ARVID J. MALMBERG, a subject of the King of Sweden, residing at Erie, in the county of Erie and State of Pennsylvania, have invented certain new and useful Improvements in Metallic Doors; and I do hereby declare the following to be a full, clear, and exact description of the invention, such as will enable others skilled in the art to which it appertains to make and use the same.

My invention relates to metallic doors and consists in certain novel and useful improvements in the same, and is a division of my application, Serial No. 799,889 filed Nov. 8, 1913.

My invention comprises the novel features hereinafter described with reference to the accompanying drawing in which I have illustrated one form in which the invention may be embodied, which has been selected by me for the purpose of illustrating the invention, and the said invention is fully disclosed in the following description and claim.

Referring to the said drawing: Figure 1 is an elevation of the interior of one side of a metallic door, showing one means of connecting the side stile and cross rail plates and omitting the panels. Fig. 2 is a plan view of the inner side of the top cross rail plate and a portion of the plates of the side stiles, showing the joining of the cross rails and side stiles by spot welding. Fig. 3 is a horizontal section taken on line 3-3 of Fig. 1.

The object of my invention is to provide a metallic door, adapted especially for use in fire proof buildings and the like, to prevent a conflagration from spreading, and thereby confine a fire to one section or room of a building. It is to be understood, however, that the device may also be employed in other relations in which its use will be advantageous or desirable.

A further object of my invention is to provide a connection between the side stiles and cross rails which will be practically indestructible in use and which will present a neat and attractive appearance from the exterior of the door.

In carrying out my invention, I form each of the side stiles of each side of the door of one integral plate, which is died or pressed

on one edge to form a molding and is bent 55 on its opposite edge to form one side of the lateral edges of the door. These moldings are provided along their length with slots in which flanges on cross rail plates are inserted and secured by means of spot welding 60 or solder.

In the drawings, the reference character A represents one side of the door and B the other side. Each of the sides of the door is composed of side stile plates 1, cross rail 65 plates 2 and panels (not shown) to which the cross rail and stile plates are connected. The stile plates 1 are provided on their inner edges with stepped molding 3 and on their outer edges with bent flanges 4, each of 70 which forms one-half of the lateral edges of the completed door. These bent flanges 4 are connected by means of screws 5 to a bar frame 5^a which extend around the interior edges of the door and forms a reinforcing 75 frame for the door. The moldings 3 are provided at periods along their length and adjacent to the plates 1 with slots 6 and shoulders 7 for a purpose about to be described. The cross rail plates 2 are provided on their lateral edges with flanges 8, 80 which are bent at right angles to said cross rail plates and pass through the slots 6 and abut against the shoulders 7 to prevent lateral displacement. These flanges 8 may be 85 secured on the interior of the door by means of solder 9, as shown in Figs. 1 and 3, which entirely incloses the flanges 8 and enters the space between the flanges and the walls of the slots 6, whereby a neat and secure 90 joint is provided.

Instead of securing the flanges 8 by means of solder, as just described, the flanges may be secured by spot welding as shown in Fig. 2. In this case metallic fillets 9 are 95 placed on the inner side of the stiles adjacent the slots 6 and which when fused become a part of the pieces welded together, where the electrodes, or other heating agency, are placed in contact with the pieces 100 to be welded, thus making a welded joint. This form of welding prevents the usual warping or buckling of the pieces welded and by this arrangement, a strong and practically indestructible connection is made and 105 one which presents a neat appearance from the exterior of the door.

While I have selected one embodiment of

my invention for the purpose of illustrating the same, I do not desire to be limited by the exact details of construction shown and described, as variations therein may be made 5 without departing from the spirit of my invention.

What I claim and desire to secure by Letters Patent is:—

10 A metallic door having side stiles, the inner edges of which are bent inwardly to form a molding, slots provided in said mold-

ings, and cross rails having flanged ends, the flanges extending through the slots and being secured therein on both sides of said flanges by a metallic fillet. 15

In testimony whereof I affix my signature, in the presence of two witnesses.

ARVID J. MALMBERG.

Witnesses:

J. K. MOORE,
ROBT. E. BARRY.
